UNITED STATES PATENT OFFICE

143,865

DESIGN FOR AN AIRPLANE

John K. Northrop and William R. Sears, Los Angeles, Calif., assignors to Northrop Aircraft, Inc., Hawthorne, Calif., a corporation of California

Application January 3, 1942, Serial No. 104,983

Term of patent 14 years

(Cl. D71—1)

To all whom it may concern:

Be it known that we, John K. Northrop and William R. Sears, citizens of the United States of America and residents of Los Angeles, county of Los Angeles, State of California, have invented a new, original, and ornamental Design for an Airplane, of which the following is a specification, reference being had to the accompanying drawings, forming part thereof.

Fig. 1 is a top plan view of an airplane showing our new design.

Fig. 2 is a front elevational view of the airplane.

Fig. 3 is a side elevational view of the airplane of Fig. 1 shown in flight posture.

Fig. 4 is a perspective view of the airplane as seen in flight from above.

We claim:

The ornamental design for an airplane, as shown.

JOHN K. NORTHRUP.
WILLIAM R. SEARS.
